(57) **CLAIM**

The ornamental design for a face pillow, as shown and described.

DESCRIPTION

FIG. 1 is a front, right, top perspective view of the face pillow, showing my new design;

FIG. 2 is a rear, left, bottom perspective view thereof;

FIG. 3 is a front elevational view thereof;

FIG. 4 is a rear elevational view thereof;

FIG. 5 is a left side view of the enlarged scale thereof;

FIG. 6 is a right side view of the enlarged scale thereof;

FIG. 7 is a top plan view thereof;

FIG. 8 is a bottom plan view thereof;

FIG. 9 is a front, right, top perspective view of its in an alternate configuration; and,

FIG. 10 is a front, right, top perspective view of its in an alternate configuration.

The dashed broken lines in the figures are for the purposes of illustrating portions of the face pillow and form no part of the claimed design.

The short-short-long dashed broken lines immediately adjacent to the claimed areas in the views represent the boundaries of the design and form no part of the claimed design.

1 Claim, 10 Drawing Sheets
